UNITED STATES PATENT OFFICE.

FRANK HARDIE, OF NEW ORLEANS, LOUISIANA.

FILTER.

No. 823,527.

Specification of Letters Patent.

Patented June 19, 1906.

Application filed October 5, 1905. Serial No. 281,450.

To all whom it may concern:

Be it known that I, FRANK HARDIE, a citizen of the United States, residing at New Orleans, in the parish of Orleans and State of Louisiana, have invented new and useful Improvements in Filters, of which the following is a specification:

My invention pertains to filters; and it contemplates the provision of a simple and inexpensive porous-wall filter possessed of large capacity and one that is adapted to be quickly and easily cleared of mud and other collected sediment without the necessity of opening the case or removing any of the parts.

The invention will be fully understood from the following description and claim when taken in connection with the accompanying drawings, forming part of this specification, in which—

Figure 1 is a view, partly in diametrical section and partly in elevation, of the filter constituting the present and preferred embodiment of my invention; and Fig. 2 is a horizontal section taken in the plane indicated by the line 2 2 of Fig. 1 looking downwardly.

Similar letters of reference designate corresponding parts in both of the views of the drawings, referring to which—

A is the case of my novel filter. The said case may be of any construction compatible with the purposes of my invention, though I prefer to have it comprise a base-section *a*, having legs *b* and also having valved outlets *c* and *d* for the discharge of collected sediment, an intermediate section *e*, and a crown-section *f*, having an opening *g* and a plate *h* for normally closing said opening and also having an air-vent *i*, the latter being preferably carried by the plate *h*, as shown.

Arranged in the case A and on the bottom thereof is an annular pure-water receptacle B, from which extends a discharge-conduit C, while extending through the bottom of the case, preferably at the point shown, is a pipe D, which is designed to be connected with a street-main or other source of supply and is preferably provided with a foraminated nozzle, as shown, whereby it is adapted to discharge the water to be filtered into the case in the form of a spray.

E are upright rods arranged in a circular series in the case and fixed to and rising from the bottom thereof. These rods E have their upper ends threaded to receive nuts F, as shown.

G is a ring or annular plate arranged on the several rods E below the nuts F.

H is an annular porous wall of circular form in cross-section arranged within the circular series of rods E and interposed between the receptacle B and the annular plate G, and I is an annular porous wall of circular form in cross-section surrounding the circular series of rods E and interposed between the receptacle B and the plate G.

In virtue of the construction thus far described it will be apparent that water entering through the pipe D will occupy the case within and without the porous walls H and I, as well as above and below said walls, also that such water can only reach the space J intermediate the walls H and I and the receptacle B, communicating with such space, after percolating through the said walls H and I. Incident to its passage through the walls H and I, which may be of stone or other porous material compatible with the purpose of my invention, the water is robbed of all foreign substance, and hence when it reaches the receptacle B and passes out through the discharge-conduit C it is in a perfectly pure state.

It will be readily gathered from the foregoing that the porous walls H and I may be quickly clamped between the annular plate G and the receptacle B in such manner that there is no liability of said walls being casually displaced, and yet when it is necessary for any reason to remove one of the walls and replace it with a new wall the same may be quickly and easily accomplished after the crown-section *f* of the case A is taken off and the annular plate G and nuts F are removed from the rods E.

From the fact that the water to be purified can pass through either of the walls H and I *en route* to the space J and the pure-water receptacle B it will be appreciated that my novel filter is possessed of large capacity in proportion to its size, which is an important desideratum in the art.

In order that the porous walls H and I may be quickly and easily cleared of collected mud and other sediment when necessity demands, I provide the mechanism shown in elevation in Fig. 1 and in horizontal section in Fig. 2. This mechanism comprises a central vertical shaft K, stepped in a block *m* on the bottom of the case A and journaled in the top of the case and bearing a collar *n*, disposed below

the top, and a spur-gear *p*, disposed above the top, a stub-shaft *r*, journaled in a suitable bearing *s* on the case-top and carrying a crank *t* and a pinion *u*, which latter is intermeshed with the spur-gear *p*, an arm *v*, which reaches laterally or radially from the upper portion of the shaft *K* and has inner and outer depending portions *w* and *x*, which terminate at the lower ends in arms *y*, upright rods *L*, disposed in slots in the arms *v* and *y* and having enlargements *z*, which bear on the arms *y*, and also having cotter-pins *a'* disposed below the arm *v*, whereby they are held against casual displacement, scrapers *M*, preferably of channel form in cross-section, fixedly connected to the rods *L* and arranged against the outer side of the outer porous wall and the inner side of the inner porous wall, respectively, as best shown in Fig. 2, and springs *N*, fixedly connected to the rods *L* and scrapers *M* and interposed between the same and the depending portions *w* and *x* on the arm *v*. The springs *N* are not connected to the depending portions *w* and *x* of the horizontally-swinging frame carried by the shaft *K*, and hence it will be observed that when the plate *h* is removed and the cotter-pins *a'* are withdrawn from the shafts *L*, either or both shafts, together with the scrapers and springs connected thereto, may be readily removed from the case.

In the practical use of my filter after the filter becomes impaired by collected mud and other sediment and it is desired to clean the walls *H* and *I* the valves *c* and *d* are opened and the shaft *K* is rotated through the medium of the crank *t* and the driving connection shown and described. When the shaft *K* is thus rotated, it will be observed that the scrapers *M* will be moved in a circular direction with respect to their porous walls and incident to such movement will be yieldingly held by the springs *N* against the said porous walls. From this it follows that the scrapers will thoroughly remove mud and collected

sediment from the porous walls and leave the same as efficient as when originally installed in the filter. The mud and other collected sediment removed from the porous walls will be carried out of the filter through the valves *c* and *d*, so that when said valves are closed and the filtering operation is resumed good results will be obtained.

Notwithstanding the practical advantages which I have hereinbefore ascribed to my novel filter it will be readily apparent that the filter is simple, compact, and inexpensive in construction and is well adapted to withstand the usage to which such apparatus is ordinarily subjected.

I claim—

In a filter, the combination of a case having an inlet for water, an annular pure-water receptacle arranged on the bottom of the case and open at its upper side and having a discharge, inner and outer annular walls of porous material arranged on and clamped against the water-receptacle and having a space between them in communication with and adapted to supply said annular receptacle and also having said space isolated from the interior of the case, a central shaft journaled in the case and extending outside the same and having a radial arm disposed within the case and provided with depending portions arranged at opposite sides of the porous walls and terminating in horizontal arms, rods movable inwardly and outwardly in the said arms and carrying scrapers, and springs interposed between the scrapers and the depending portions of the first-mentioned arm, whereby the scrapers are yieldingly held against the porous walls.

In testimony whereof I have hereunto set my hand in presence of two subscribing witnesses.

FRANK HARDIE.
